SAFETY LOCK

Albert A. J. Cohan, Philadelphia, Pa.

Application January 11, 1945, Serial No. 572,337

4 Claims. (Cl. 292—346)

This invention relates to safety locks and pertains more particularly to improvements in non-tamperable night latches for doors.

The principal purpose of the invention is to provide a night latch with simple, durable and automatically operable safety devices which effectively guard the main bolt of the latch from being pried open or cut off by a tool inserted in the crack between the closed door and the jamb, and which also afford auxiliary locking means and thus increase the security of the improved lock.

A recommended embodiment of the invention is shown in the accompanying drawing, but it will be understood that the structural details of the mechanism herein illustrated and described may be varied to suit particular conditions or installations without departing from the essence of the invention defined in the appended claims. In the drawing,

Fig. 1 is an elevation of the improved safety lock as applied to the inside of a closed door;

Fig. 2 is a lower edge view of the lock, to larger scale, with a portion of the lock proper broken away and with the strike or keeper shown in section.

Fig. 3 is an end view of the outer face of the strike;

Fig. 4 is an end view of the outer face of the lock proper; and

Fig. 5 is a section on line 5—5 of Fig. 3, with the face plate of the strike partly broken away.

The improved safety lock comprises the lock proper 10 which is screwed on the inside of the door 11 and which may be of the ordinary night latch type having a spring-pressed bolt 12 movable to inoperative position by a knob 13 and held either open or closed by the usual thumb catch 14; and keeper or strike 15 having a face plate 16, screwed to the jamb 17, and adapted to receive the beveled face 18 of the bolt 12, as indicated by the broken lines of Fig. 2. These parts may be of any desired size, shape or construction and the internal mechanism of the lock proper is immaterial to the present invention which is concerned with a safety plate 19 incorporated in the strike and actuated by lugs or jaws 20 on the face of the lock 10.

The safety plate 19 is a relatively wide piece of stout metal, slideable across the bottom 21 of the strike and guided in notches 22 (Fig. 3) of the face 16. It is normally retracted within the strike by a pair of coiled springs 23 suitably attached to the back of the strike. As here shown (Fig. 5) the back of the strike has a pair of apertures receiving the spring ends and the latter

are retained by a bar 24 passed through their end loops.

The plate 19 has a pair of upstanding cam members 25 spaced apart so that the bolt end 18 may be received therebetween, and also spaced from the forward edge of the safety plate so that the latter may be received in a slot 26 in the face 27 of the lock 10 when the lock is secured (Fig. 2). The rearward edges of the cams 25 are inclined at an angle of approximately 45 degrees, and the rearward or inner edges of the lock lugs 20 are similarly inclined to cooperate therewith. Said lugs are spaced a distance equivalent to the lateral spacing of the cams, so that the inclined surfaces of the cooperating elements are engaged with a sliding action when the door is closed, thereby automatically projecting the safety plate 19 to locking position as shown in Fig. 2.

The top of the strike has a pair of slots 28 through which the respective lugs 20 pass when the door is closed, and a central tongue 29 depending from the top of the strike at the front thereof engages the top of the end 18 of the main bolt 12 when the latter is closed, to prevent the opening of the door until the bolt is withdrawn.

The closed bolt is thus protected against tampering by the automatically closed safety plate which bridges the crack 30 between the door and jamb exteriorly of the bolt and thus prevents the forcing of the bolt by an implement inserted in the crack and pressed against the beveled face of the bolt, and also by the interengaged cam and lug members which further impede any attempt to saw through the safety plate and the bolt. The safety plate also serves as an auxiliary bolt, but that plate is automatically withdrawn by the retracting springs 23 when the door is opened to release the lugs 20 from engagement with the cams 25, after the main bolt is retracted.

I claim:

1. In a night latch of the character described having a lock attachable to a door, a strike attachable to a jamb and a bolt movable from the lock into the strike, safety devices comprising a lug projecting from the face of the lock and adapted to enter the strike, a plate disposed within the strike and movable relatively thereto to engage the face of the lock, said plate having a cam engaged by said lug when the door is closed thereby automatically to project the plate from the strike toward the lock, and resilient means normally retracting said plate.

2. In a night latch of the character described having a lock attachable to a door, a strike attachable to a jamb and a bolt movable from the

lock into the strike, safety devices comprising a lug projecting from the face of the lock and adapted to enter the strike, a plate disposed within the strike and movable relatively thereto to engage the face of the lock, the face of the lock having a slot receiving the end of the projected plate, said plate having a cam engaged by said lug when the door is closed thereby automatically to project the plate from the strike into the lock, and resilient means normally retracting said plate. 10

3. In a night latch of the character described having a lock attachable to a door, a strike attachable to a jamb and a bolt movable from the lock into the strike, safety devices comprising a pair of spaced lugs projecting from the face of the lock on opposite sides of its bolt, the front of the strike having complementary notches through which the lugs enter the strike, a plate slideable within the strike toward and from the face of the lock, said plate having a pair of spaced cams engaged by said lugs when the door

is closed thereby automatically to project the plate from the strike and into engagement with the face of the lock, and spring means normally retracting said plate into the strike. 5

4. In a night latch of the character described having a lock attachable to a door, a strike attachable to a jamb and a bolt movable from the lock into the strike, safety devices comprising a pair of spaced lugs projecting from the face of the lock on opposite sides of its bolt, the front of the strike having complementary notches through which the lugs enter the strike, a plate slideable within the strike toward and from the face of the lock, the face of the lock having a slot receiving the end of the projected plate, said plate having a pair of spaced cams engaged by said lugs when the door is closed thereby automatically to project the plate from the strike and into said slot, and spring means normally retracting said plate into the strike. 15 20

ALBERT A. J. COHAN.
